UNITED STATES PATENT OFFICE.

ABRAHAM LEVINE, OF ELIZABETH, NEW JERSEY, ASSIGNOR TO PRESTO LOCK CORPORATION, OF NEW YORK, N. Y., A CORPORATION OF NEW YORK.

DESIGN FOR A LOCK.

Application filed June 2, 1926. Serial No. 17,922. Term of patent 3½ years.

To all whom it may concern:

Be it known that I, ABRAHAM LEVINE, a citizen of the United States, and a resident of Elizabeth, county of Union, and State of New Jersey, have invented a new, original, and ornamental Design for a Lock, of which the following is a specification, reference being had to the accompanying drawing, forming part of this specification, wherein:—

Fig. 1 is a face view of my device;

Fig. 2 is an end view of Fig. 1.

I claim:

The ornamental design for a lock as shown.

In witness whereof, I have hereunto signed my name.

ABRAHAM LEVINE.
